ORGAN CONSOLE

William Millington, Grand Rapids, Mich., and Wilbur M. Day, Kenwood, Ohio, assignors to The Baldwin Piano Company, Cincinnati, Ohio, a corporation of Ohio

Application June 29, 1956, Serial No. 42,092

Term of patent 14 years

(Cl. D56—2)

The figure is a perspective view of an organ console showing our new design.

This is a continuation-in-part of our copending application Serial No. D.39,191, filed December 7, 1955, and entitled Organ Console, now abandoned.

We claim:

The ornamental design for an organ console, substantially as shown.
